UNITED STATES PATENT OFFICE.

MICHAEL FRASCADORE AND ROMEO VALLONE, OF PHILADELPHIA, PENNSYLVANIA.

REAR LAMP FOR AUTOMOBILES.

Application filed October 24, 1922. Serial No. 596,563.

To all whom it may concern:

Be it known that we, MICHAEL FRASCADORE and ROMEO VALLONE, residing at Philadelphia, county of Philadelphia, and State of Pennsylvania, have invented certain new and useful Improvements in Rear Lamps for Automobiles, of which the following is a specification:

Our invention relates to rear lamps and has for its object to provide a lamp of a simple and compact construction embodying the features of a license holder, a tail light and an advertising lamp.

These objects, and other advantageous ends which will be described hereinafter, we attain in the following manner, reference being had to the accompanying drawings in which—

Figure 1 is a front view of a lamp constructed in accordance with our invention,

Figure 2 a top plan view of Figure 1,

Figure 3 a section on line 3—3 of Figure 1,

Figure 4 a section on line 4—4 of Figure 1,

Figure 5 a section on line 5—5 of Figure 4.

Referring to the drawings, 1 is a casing, preferably of a triangular shape, having a rear wall 2, an inclined top 3 and a removable front wall 4 provided with an opening 5 and a perforated name 6 of the owner or vehicle. The front wall has formed at its bottom a channel 7 adapted to receive a transparent plate 8 which covers opening 5 and perforated name 6. Lugs 9 extend downwardly from top 3 and abut the inner bottom of channel 7. The top of the front wall is bent to form a flange 10 from which extend spring-fingers 11 adapted to engage the inclined top 3 and thereby hold the transparent plate in place. The inner surface 12 of the inclined top serves as a reflector to reflect the light from a bulb 13 held by the rear wall. The rear wall has an extension 14 for holding a license tag 15 by screws or other securing means.

When the lamp is in use, bulb 13 is illuminated and its light is reflected on the transparent plate. To renew the bulb or the transparent plate, access to the interior of the casing is easily gained, by removing the front wall.

To replace the front wall, the channel is placed against lugs 9 and the spring-fingers are snapped over the inclined top thereby

securely holding the front wall in position.

While we have described our invention as taking a particular form, it will be understood that the various parts of our invention may be changed without departing from the spirit thereof, and hence we do not limit ourselves to the precise construction set forth, but consider that we are at liberty to make such changes and alterations as fairly come within the scope of the appended claims.

Having thus described our invention, what we claim as new and desire to secure by Letters Patent is:—

1. A rear lamp for automobiles comprising a rear wall; a front wall having an opening; a top wall sloping rearwardly; resilient means affording attachment of the front wall to the top wall; a channeled lower edge on the front wall; a transparent closure member in the channel covering the opening; and illuminating means to the rear of the closure member.

2. A lamp for automobiles comprising a rear wall; a front wall having an opening; a top wall sloping rearwardly; a channeled lower edge on the front wall; extended portions on the top wall insertable in the channel; a transparent plate in the channel covering the opening; and illuminating means to the rear of the transparent plate.

3. A rear lamp for vehicles including a rear wall; a top sloping upwardly from the rear wall and downwardly toward its opposite ends; a removable front wall having an opening and a perforated name formed therein and provided with fingers affording means of attachment to the top wall; a transparent plate on the inner side of the front wall; and illuminating means to the rear of the transparent plate.

4. A rear lamp for automobiles comprising a casing having a removable front wall provided with an opening and a channeled lower edge; means for detachably securing the front wall to the casing; a transparent plate in the channel covering the opening; extended portions on the top wall of the casing insertable in the channel, and illuminating means within the casing.

5. A rear lamp for automobiles comprising a rear wall; a removable front wall having an opening and a perforated name; a top sloping upward from the rear wall to the front wall; a channeled lower edge on the front wall; spring-fingers on the upper

edge of the front wall; a transparent plate in the channel covering the opening and perforated name, and illuminating means between the front and rear walls.

6. A rear lamp for automobiles comprising a rear wall; a removable front wall having an opening and a perforated name; a top sloping upward from the rear wall to the front wall; a channeled edge on the 10 front wall; lugs depending from the top adapted to engage the channel; spring-fingers on the upper edge of the front wall;

a transparent plate in the channel covering the opening and perforated name, and illuminating means between the front and rear ¹⁵ walls.

In testimony whereof we have signed our names to this specification in the presence of two subscribing witnesses.

MICHAEL FRASCADORE.
ROMEO VALLONE.
